(57) **CLAIM**

The ornamental design for a medical rehabilitation device, as shown and described.

DESCRIPTION

FIG. 1 is a front and right side perspective view of a medical rehabilitation device, showing my new design;

FIG. 2 is a left side view thereof;

FIG. 3 is a right side view thereof;

FIG. 4 is a front view thereof;

FIG. 5 is a rear view thereof;

FIG. 6 is a front and right side perspective view thereof in a raised position;

FIG. 7 is a top view thereof in the position of FIG. 1; and,
FIG. 8 is a bottom view thereof.

The features shown in broken lines show portions of the medical rehabilitation device that form no part of the claimed design.
